UNITED STATES PATENT OFFICE.

FRANK E. MATTHEWS, OF BRIDGEPORT, CONNECTICUT, ASSIGNOR TO DANIEL J. WILLIAMS AND HENRY E. DINESON, DOING BUSINESS UNDER THE NAME OF THE CONNECTICUT TOOL AND ENGINEERING COMPANY, OF BRIDGEPORT, CONNECTICUT.

PULLEY AND SHEATH THEREFOR.

1,392,957.

Specification of Letters Patent. Patented Oct. 11, 1921.

Application filed April 28, 1921. Serial No. 465,156.

To all whom it may concern:

Be it known that I, FRANK E. MATTHEWS, a citizen of the United States, and resident of Bridgeport, in the county of Fairfield and 5 State of Connecticut, have invented certain new and useful Improvements in Pulleys and Sheaths Therefor, of which the following is a specification.

The object of the present invention is to 10 provide a novelly constructed pulley of simple, durable, practical and economical construction, the same consisting of but a single piece of suitable sheet metal, and to equip the pulley with a one piece sheath of im- 15 proved design.

With the above and other objects in view, the invention comprises the construction, arrangement and combination of parts now to be fully described and hereinafter specifically claimed, it being understood that such changes in details of construction may be made as fall within the spirit of the invention and the scope of the claims.

In the accompanying drawing forming a 25 part of this specification,

Figure 1 is a side elevational view of the improved pulley and sheath;

Fig. 2 is an edge view corresponding with Fig. 1;

30 Fig. 3 is a transverse sectional view of the pulley;

Fig. 4 is a plan view, on a reduced scale, of a blank for forming the sheath; and

Fig. 5 is a sectional view on line 5-5 in 35 Fig. 2, looking in the direction of the arrows.

As already mentioned, both the pulley and sheath consist of but a single piece of suitable sheet metal.

40 The pulley may be formed from a disk of sheet metal, the body portion of said disk constituting the body portion 10 of said pulley, and said disk being shaped adjacent its margin to produce a groove 11 in the central portion of which is in alinement with and supported by the body portion of said pulley. To this end the disk may be first bent in about the direction shown along the circumference denoted 12 to produce the flaring portion 13. It may then be bent in reverse direction along the circumference denoted 14 to produce the groove, as will be understood.

To supply a bearing for body portion 10,

an opening 15 is provided at the center 55 thereof, and arms 16, struck from said body portion and suitably bent, are provided with openings 17 which align with each other and with opening 15. Slots 18 in Fig. 1 define the outlines of the material in the disk blank 60 which constitutes arms 16 in the finished pulley, as is obvious. Any number of arms may be employed. As shown, I utilize six, alternate arms extending in opposite directions from the body portion of the pulley. In 65 constructing the arms to serve their purpose, each is first bent away from the body portion, preferably at approximate right-angles, along the line denoted 19 and is then bent, preferably at right-angles, along the line 70 denoted 20 and toward the axis of the pulley, the portions of the arms which have openings 17 being in parallel relation to overlap and engage each other. Numeral 21 denotes a suitable bushing seated in all of openings 75 15 and 17, 22 denotes the shaft of the pulley, and 23 denotes roller bearings in the bushing and surrounding the shaft.

In order that bushing 21 may be inserted in the bearing of the pulley without the liability of arms 16 first to receive the bushing becoming bent, the metal adjacent opening 15 may be drawn to provide an annular flange 24 extending from the body portion, and the metal adjacent opening 17 of that 85 arm 16 which is closest said opening 15 may be correspondingly drawn to provide an annular flange 25, the arrangement being such that in the finished pulley the outer ends of said flanges rest against each other, as will 90 be more clear from Fig. 3.

A blank suitable for forming the sheath is disclosed in Fig. 4. It consists of a small central portion 26 from which extend ears 27 and eye portions 28, said ears and eye portions, respectively, being located opposite each other. The ears are of general half-circular configuration as disclosed, and in the finished sheath they are parallel with each other to inclose about one-half of the 100 pulley, the circumferential margins of said ears interlapping as best shown at 29 in Fig. 2. The eye portions 28 in the finished sheath constitute an eye 30 by means of which the sheath and pulley are supported. 105

In forming the sheath from the blank shown, said blank is bent at right-angles in the same direction along both of lines 31 to

position the ears in parallel relation, the circumferential margins of said ears being then shaped to interlap in the manner already suggested. If preferred, the outer portions 5 of said ears may be caused to flare, as denoted at 32, for an obvious purpose. In producing eye 30 the blank is suitably bent along lines 33 and 34 to position the eye portions adjacent each other, and said portions 10 are then made to interlap after the fashion indicated at 35 and more particularly shown in Fig. 5.

Openings 36 in the sheath receive the shaft 15 of the pulley.

Having thus fully described the invention, what I claim and desire to secure by Letters Patent, is:

1. A pulley consisting of a single disk of metal shaped adjacent its margin to provide 20 a pulley groove and constructed at its center to provide a bearing, said bearing comprising an opening in the metal of said pulley and openings in arms struck from said metal and arranged in parallel relation and in 25 alinement with said opening in said metal.

2. A pulley consisting of a single disk of sheet metal shaped adjacent its margin to provide a pulley groove and constructed at its center to provide a bearing, said bearing 30 comprising an opening in the metal of said pulley and openings in arms struck from said metal, and said arms being positioned upon opposite sides of said pulley.

3. A pulley consisting of a single disk of sheet metal shaped at its margin to provide 35 a pulley groove and constructed at its center to provide a bearing for said pulley, said bearing comprising a plurality of arms

struck from said disk and arranged at opposite sides thereof, said arms having portions 40 arranged parallel with said disk and overlapping each other, and said portions having alining openings.

4. A pulley consisting of a single disk of sheet metal shaped adjacent its margin to 45 provide a pulley groove and constructed at its center to provide a bearing for said pulley, said bearing comprising a plurality of arms struck from said disk and arranged at opposite sides thereof, said arms having 50 portions arranged parallel with said disk and overlapping and engaging each other, and said portions and disk having alining openings.

5. A pulley as specified in claim 4, wherein 55 the disk is provided adjacent its opening with an annular flange and one of said arms is provided with a similar flange, said flanges adapted to engage each other for the purpose specified.

6. A sheath consisting of a single blank of sheet metal, said blank comprising a small central portion, parallel ears extending therefrom and adapted to inclose a pulley, and an eye for said sheath, said eye consisting of eye portions integrally carried by 65 said central portion.

7. A sheath as specified in claim 6, wherein in the ears are of general half-circular configuration and the eye portions and ears, respectively, interlap with each other.

Signed at Bridgeport, in the county of Fairfield, and State of Connecticut this 26th day of April, A. D. 1921.

FRANK E. MATTHEWS.
